WILLIAM A. EDWARDS, OF CHICAGO, ILLINOIS, ASSIGNEE TO STEWART-WARNER SPEEDOMETER CORPORATION, OF CHICAGO, ILLINOIS, A CORPORATION OF VIRGINIA.

CARBURETER.

1,390,681.

Specification of Letters Patent. Patented Sept. 13, 1921.

Application filed November 23, 1918. Serial No. 263,799.

To all whom it may concern:

Be it known that I, WILLIAM A. EDWARDS, a citizen of the United States, residing at Chicago, in the county of Cook and State of Illinois, have invented certain new and useful Improvements in Carbureters, of which the following is a specification, reference being had to the accompanying drawings, forming a part thereof.

- 10 The purpose of this invention is to provide an improved construction of carbureter for an internal combustion engine adapted more perfectly than structures heretofore employed to accommodate the liquid fuel supply to the air supply under varying running conditions. It consists in the elements and features of construction shown and described as indicated in the claims.
- 15 In the drawings:—
- 20 Figure 1 is an axial section of a carbureter embodying this invention.
- 25 Fig. 2 is a section at the line, 2—2, on Fig. 1.
- 30 Fig. 3 is a bottom side view of the same.
- 35 The carbureter shown in the drawings comprises a liquid fuel supply chamber, 1, having connections through a plug, 1^a, at the top with a source of liquid fuel supply and means for controlling this supply to prevent overflow or flooding by means of a float 6 in the chamber operating the controlling valve, 1^b, in a manner well understood and requiring neither particular illustration nor description. The body of the
- 40 liquid fuel chamber, 1, is preferably formed integrally with the Venturi tube, 2, which extends axially through the said liquid fuel chamber reducing the latter to annular form as to its liquid-containing space, said annular chamber being closed at the bottom by a removable cap, 3, which affords convenient access to the parts within the liquid chamber for their insertion and adjustment and repair. The main Venturi tube begins to converge toward its throat or most constricted part, at the top of the float chamber, and therefore at a considerable distance above the top of the level-governing float, 6, at its highest position, which is of course above the governed level of the liquid supply in the chamber. Within the main Venturi tube, 2, there is positioned a mouth piece, 4, coaxial with the main Venturi tube and preferably itself in the form of a Venturi tube
- 45 and hereinafter referred to as the auxiliary
- 50 Venturi tube or Venturi mouth piece. This mouth piece, 4, is positioned and secured within the main Venturi tube by having at its lower end three radially projecting ribs, 4^a, constituting a spider by which the Venturi mouth piece is centered in the main Venturi tube, which is counterbored from its lower end to form a shoulder, 2^a, against which the said radial spider projections of the Venturi mouth piece or the ring, 4^b, connecting them, are stopped at the upper end, a circular spring key, 5, being engaged in a groove 2^b, formed in the interior wall of the lower part of the main Venturi tube for stopping the Venturi mouth piece and retaining it with its spider stopped against the shoulder, 2^a. The liquid is supplied to the mixing chamber, or space, in the Venturi tube in which it is intermixed with air, by a duct which comprises a pipe, 7, depending from a fitting, 8, which is screwed into the top of the liquid fuel chamber and which has a reduced orifice, 8^a, leading through it for connection with a small pocket, 9, formed in the web of the casting which constitutes the top of the liquid fuel chamber, from which pocket a tube, 10, extends across the annular space between the main Venturi tube, 2, and the Venturi mouth piece, 4, into which said tube 10, is screwed at its inner end, so that the duct formed by the tube discharges in the mouth piece passage at a point a little above the constriction thereof which is at a considerable distance above the governed level of the liquid supply in the float chamber, 6, as indicated. A throttle valve, 12, is positioned in the Venturi tube, 2, that is to say, in the passage leading to the engine intake at a point considerably beyond the construction of said Venturi tube, and as illustrated at a point just beyond the tapered portion thereof. From the pocket, 9, a duct, 11, formed in an extension of the integral casting which constitutes the Venturi tube and the body of the liquid fuel chamber, leads back into the engine intake passage—the extension of the Venturi tube passage, entering the same just beyond the point of seating of the throttle valve. Preferably the discharge of this duct in the engine intake passage beyond the throttle valve is restricted by means of a plug, 13, which is inserted through a hole bored in the boss, 14, whose end is afterward closed by a plug, 16, said restricting plug, 110

13, having the passage formed axially through it substantially of the same diameter as the passage, 8^a, and as the axial passage of the tube, 10, which leads into the 5 Venturi mouth piece passage. In addition to the duct thus far described, there is provided another duct, 15, formed in the casting leading from the upper part of the liquid fuel chamber into the main Venturi 10 tube into which it opens at a point approximately in the transverse plane of the discharge mouth of the Venturi mouth piece, a little beyond the constriction of the main Venturi tube.

15 The operation of the device above described is as follows:

When the engine is idling, the throttle valve, 12, being closed as shown in Fig. 1, and some leakage of air occurring past that 20 valve, which is intentionally made loose fitting in the passage in which it is located, the suction of the engine will lift a limited amount of liquid fuel from the fuel chamber, 1, through the continuous passage 25 formed by the ducts, 8^a and 11; but by reason of the absence of any substantial air current through the main Venturi tube, no liquid fuel will be drawn through the tube, 10, leading from the pocket, 9, into the Venturi mouth piece; but on the contrary, air 30 will be drawn in through said Venturi mouth piece passage and through said tube, 10, into the pocket, 9, and mixing with the liquid fuel passing through that pocket will 35 pass up through the duct, 11, and be discharged with the liquid fuel,—a partial mixture of air and liquid fuel,—into the engine intake passage beyond the throttle valve, where it will receive a further admixture 40 of air passing around the throttle valve, thus affording a suitable mixture for serving the engine idling or with very light load. When the engine is to be connected for carrying load, the throttle valve being 45 open, the suction of the engine producing an inward air current which will have a high velocity at the constriction of the main Venturi tube, produces by entrainment, in addition to the suction, a rapid inrush of air 50 through the Venturi mouth piece, the velocity of which will be maximum just beyond or inward from the constriction of the Venturi passage in the mouth piece, and in turn will produce a strong suction and entrainment effect for lifting the fuel from the liquid fuel chamber and causing it to 55 be discharged through the tube, 10, into the air current entering through the Venturi mouth piece passage. The liquid fuel chamber 60 being limitedly open to atmospheric pressure through the restricted atmosphere vent port, 17, consisting of a small bore through a plug, 17^a, the result of this first inrush of air following the opening of the 65 throttle valve will be to "starve" the en-

gine by taking in a largely increased amount of air before there is time for the suction to pick up the liquid fuel, lifting it from the chamber, 1, through the pipe, 7, and ducts, 8^a and 10. The "lag" as it is commonly called, of the liquid fuel, might be diminished by making the passages larger and thereby more free and by making the governed level of the liquid in the chamber, 1, higher; but when this is done so that the 70 engine is not actually starved in the first stroke after opening the throttle, a greatly increased flow of liquid results, as soon as the lag is passed, in too rich a mixture causing diminished efficiency or total stoppage, 80 which is liable to occur immediately following the first stroke or two. Both the starving and the over-enriching are prevented by the structure shown. The suction having been operating through the duct 85 in the plug, 13, and pipe, 11, for lifting the liquid during the idling of the engine, the liquid will be already standing in the duct, 7, and in the chamber, 9, ready to enter the duct, 10, before the first experience of suction through the vacuum tube results from opening the throttle valve; and substantially full atmospheric pressure being, for the instant, operative on the surface of the liquid in the chamber, 1, the liquid will respond to the suction about as quickly as the air responds, and the first charge drawn in after the opening of the throttle will be an effective mixture, and not a starvation mixture because the liquid is already in the 90 pocket, 9, and the reduction of pressure on the liquid in the chamber, 1, which will eventually result from the suction operating through the duct, 15, will not have been experienced for an appreciable interval after 95 the first stroke or two of the engine, to a degree sufficient to defeat the in-flow of the suction upon the liquid already lifted in the duct, 7—8^a, and into the pocket, 9, and the duct, 10. In the immediately succeeding strokes of the engine, however, the suction operating through the duct, 15, counteracts the tendency to an over-rich mixture by affording an avenue for the suction which results from the comparatively high degree 100 of partial vacuum existing in the main Venturi tube at the point just beyond its constriction, reducing the pressure upon the liquid fuel in the fuel chamber balancing the suction operating through the Venturi 105 mouth piece tube a duct, 10, and causing less liquid to be sucked in by that passage than would be the case if there were not provided any means for reducing the pressure upon the liquid in the liquid fuel chamber 110 below atmospheric. The result is very prompt acceleration or picking up of speed by the engine under load upon opening the throttle valve without a succeeding loss from over-richness. When the engine is 115 120 125 130

idling the throttle valve being at closed position, the duct, 15, supplements the port, 17, in admitting atmospheric pressure to the fuel chamber, 1, and thereby gives full effect 5 to the suction operating through the restricted duct in the plug, 13, for taking a proper quantity of liquid fuel beyond the throttle valve.

Without regard to the effect of the duct, 10 15, for the purpose described, the Venturi form of the mouth piece passage is important for two reasons, first, because being tapered widening from a point below the level of constriction of the main Venturi 20 tube to greatest diameter approximately at the plane of that constriction, it increases the relative constriction of the main Venturi tube, that is to say, it reduces the cross-sectional area open for air passage at the 25 constriction of the main Venturi tube to a comparatively narrow annular space while it reduces to a much less degree the cross-sectional area of the anterior portion or entrance path of the air through the main 30 Venturi tube, thus causing the air passing the constriction of the main Venturi tube to have a higher velocity than it would otherwise have. This increased velocity of air passing the mouth of the Venturi-shaped mouth piece, tends to produce a stronger current through that mouth piece passage, which in turn has its highest velocity at the constriction of said Venturi mouth piece 35 passage, thereby exerting the maximum entrainment or suction effect for lifting the liquid fuel from the fuel supply chamber for mixture with the air thus entering and moving at high velocity through the Venturi mouth piece passage. The result is the aspiration of the liquid fuel and its thorough 40 intermixture with the primary air supply which enters through the Venturi mouth piece passage, which prepares it for more thorough mixture than would otherwise result 45 when it emerges from the wide discharge mouth of the Venturi nozzle into the high velocity air current passing through the main Venturi tube at the constriction of the latter.

50 It will be observed that the velocity of the air passing through the main Venturi tube at the level of the discharge mouth of the Venturi mouth piece and of the duct, 15, will be less than the velocity of the air passing 55 the discharge mouth of the tube, 10, just above the constriction of the Venturi mouth piece passage, because the effect of said Venturi mouth piece passage is to give an increased velocity to the air at its constriction; and this high velocity, it will be observed, produces a stronger suction at the 60 discharge mouth of the tube, 10, in the Venturi mouth piece passage than that which is produced through the duct, 15. It will be 65 also observed that it is necessary that there

should be a greater suction at the first mentioned point than at the second, since it is only by virtue of the difference in suction and the resulting difference in pressure upon the liquid in the liquid supply chamber that the liquid fuel will be lifted from the liquid fuel supply chamber for discharge through the duct, 10, and admixture with the air as described; and it is primarily for producing this difference in suction at the two points 75 that the mouth piece passage is made of Venturi form as described.

I claim:—

1. In a carbureter, in combination with a liquid fuel chamber and liquid level governing means therefor, a main air supply passage open at one end for air inlet, and adapted for connection at the other end with the engine intake, said passage being constructed for causing reduction of pressure to result 80 at a predetermined point therein from the air currents therethrough; a fuel inlet mouth-piece situated in the main air supply passage having its discharge end located proximate to the point of reduced pressure 85 and open at the opposite end for air inlet, a liquid fuel discharge duct extending horizontally for discharging into the air current entering through said fuel inlet mouth-piece; and at a considerable distance above 90 the governed liquid level of the fuel supply chamber, a chamber substantially at the level of said fuel discharge, from which chamber said discharge duct leads to its discharge end; a duct leading upward from the fuel 95 supply chamber located at the fuel discharge level and delivering at its upper end in said last mentioned chamber, and a duct leading from the top of said chamber to a point in the intake passage beyond the seating point 100 of the throttle valve therein.

2. In a carbureter, in combination with a liquid fuel chamber, a main air supply passage open at one end for air inlet, and adapted for connection at the other end with the engine intake, said passage being constructed for causing reduction of pressure to result 110 at a predetermined point therein from air current therethrough, a fuel inlet mouth-piece situated in the main air supply passage, having its discharge end located proximate to the point of reduced pressure in the main air intake, and open at the opposite end for air inlet; a liquid fuel discharge duct extending substantially horizontally 115 for discharge into the air current entering through said fuel inlet mouth-piece; a throttle valve located in the main air supply passage beyond the point of low pressure therein, a liquid fuel supply by-pass passage leading from the liquid supply chamber for discharge into the intake passage beyond the seating point of the throttle valve therein, said by-pass passage leading past the level 120 of the horizontally-extending liquid fuel dis- 125

130

charge duct and being connected therewith, said by-pass passage being relatively reduced in diameter below the point of its connection with the liquid fuel discharge passage and at its discharge into the intake passage beyond the throttle valve, whereby a supply of liquid fuel drawn into said by-pass passage by the suction when the throttle valve is closed, is retarded in its return

to the fuel supply chamber, and is held 10 available at and above the level of said horizontally-extending liquid fuel discharge passage when suction is operative through said passage.

In testimony whereof, I have hereunto set 15 my hand at Chicago, Illinois, this 21st day of November, 1918.

WILLIAM A. EDWARDS.
